UNITED STATES PATENT OFFICE.

HEINRICH CONZELMANN, OF STUTTGART, GERMANY, ASSIGNOR TO ROBERT BOSCH AKTIENGESELLSCHAFT, OF STUTTGART, GERMANY.

SWITCH.

Application filed November 9, 1921. Serial No. 513,958.

To all whom it may concern:

Be it known that I, HEINRICH CONZELMANN, a citizen of Germany, residing at Stuttgart, Germany, have invented certain new and useful Improvements in Switches, of which the following is a specification.

The present invention relates to a switch for electric installations, especially for electric ignition and lighting installations of power vehicles. There is, at the switch casing, a handle which may assume several positions, and besides it a push button is provided. The switch handle may serve, for instance, for throwing into, and out of, circuit various ignition devices or lamps or the like, and the push button may serve, for instance, for operating a starting electromotor or a starting ignition device or the like.

There are already switches known which have a push button located in the centre portion of the switch handle, and there has also been provided for them a special detachable key which in a certain position locks that handle and may then be drawn off the switch casing.

The distinguishing difference between these known switches and the novel one consists in the feature that the switch handle with the push button inserted into it may itself be drawn off the switch casing, whereby, of course, the same protection against unauthorized use of the switch is offered as is done by the specially detachable locking key of the known switch; but this special key and the locking device is now dispensed with. Switches with a detachable handle are also known, it is true, but no push-button is attached to them.

In order to make my invention more clear, I refer to the accompanying drawing, in which Fig. 1 is a vertical section through a switch constructed according to this invention, and Fig. 2 is partly a plan and partly a vertical section through the circumferential wall of the front portion of the casing, a portion of the front wall of the casing being broken away.

e' and e^2 are contact plates of which the one is attached to the bottom portion of the switch casing and the other is attached to the top portion of the same; they co-operate with slip springs b affixed to a rotary member c that may be actuated from the outside of the casing and adjusted to various positions. This rotary motion is effected by the

switch lever d , the central spindle f of which forms a kind of key which fits into a correspondingly shaped central aperture of the member c . The spindle f is hollow and serves as guide for the shaft of a push button h arranged in the body-portion of the handle, as shown. Behind the push button shaft is a contact plate i attached to the bottom of the casing; by pressing the button h inwards against that plate i a certain circuit is closed.

At a certain position of the switch handle, for instance in the position indicated by the O at the top of Fig. 2 the beard of the key formed by the spindle f may be drawn out through a correspondingly shaped slot g provided in the front plate of the switch casing; in other words, the handle d with its push button h may then be drawn off that casing. This having been done, it is extremely difficult to turn the member c with the contact springs b or to establish an electric connection between the contact plates e' and i . It is, thus, practically, impossible for an unauthorized person to actuate the switch.

Having now described my invention, what I claim as new and desire to secure by Letters Patent of the United States is:

1. A switch, especially for electric installations of power vehicles, comprising, in combination, a casing; stationary and movable contacts in said casing, said movable contacts being mounted for movement into and out of engagement with certain of said stationary contacts; a handle adapted to be coupled with the movable contacts and to be detached from said casing; and a push-button in said handle carrying a terminal adapted upon operation to engage one of said stationary contacts, for the purpose set forth.

2. A switch comprising, in combination, a casing, a stationary contact enclosed within said casing, a movable contact mounted within said casing for movement into and out of engagement with said stationary contact, handle means detachably mounted through a wall of said casing adapted to be coupled with said movable contact and to be detached from said casing, a push-button carried by said handle means and detachable therewith from said casing, and another stationary contact within said casing adapted to be engaged by said push-button.

3. A switch comprising, in combination, a

casing, stationary contacts enclosed within said casing, a movable contact mounted within said casing for movement into and out of engagement with a stationary contact, handle means detachably mounted through a wall of said casing adapted to be coupled with said movable contact and to be detached from said casing, a movable contact piece carried by said handle means and detachable therewith from said casing and adapted to engage one of said stationary contacts.

4. A switch comprising, in combination, a casing, stationary and movable contacts enclosed within said casing, said movable contacts mounted for movement into and out of engagement with certain of said stationary contacts, handle means detachably mounted through a wall of said casing, adapted to be coupled with said movable contacts and to be detached from said casing, and a push-button carried by said handle means normally out of engagement with said contacts within said casing and adapted, upon operation to engage one of said stationary contacts.

5. A switch comprising, in combination, a casing, stationary contacts enclosed within said casing, a rotary member mounted within said casing adjacent a wall thereof movable contacts affixed to said member, handle means for said rotary member, said member and handle means having complementary parts formed to detachably couple said handle means to said member for rotation of the latter, said wall being apertured to permit said coupling, and a push button carried by said handle means and adapted to engage one of said stationary contacts within said casing.

6. A switch comprising, in combination, a casing, stationary contacts enclosed within said casing, a rotary member mounted within said casing adjacent a wall thereof, movable contacts affixed to said rotary member, handle means for said rotary member, said rotary member and handle means having respectively a cooperating key-way and key formed to detachably couple said member and handle means together for rotation of said member, said wall being provided with a key hole providing for the insertion and withdrawal of said handle means and a push button carried by said handle means and adapted with said handle means inserted to be operated into engagement with one of said stationary contacts.

7. A switch comprising, in combination, a casing, stationary contacts enclosed within said casing, a rotary member mounted within said casing adjacent a wall thereof, movable contacts affixed to said rotary member, a switch lever having a hollow spindle and key projections upon said spindle, said wall and rotary member being apertured for the insertion of said spindle and said rotary member having keyways cooperating with said key projections for rotation of said member, and a push-button mounted on said lever having a contact-bearing stem extending through said hollow spindle for engagement with one of said stationary contacts.

In testimony whereof I have affixed my signature in presence of two witnesses.

HEINRICH CONZELMANN.
